THOMAS E. CLARK AND JAMES E. CLARK, OF DETROIT, MICHIGAN, ASSIGNEES TO
CONTINUOUS TRAIN CONTROL CORPORATION, OF DETROIT, MICHIGAN, A CORPORA-
TION OF MICHIGAN.

PROCESS FOR TUNING TRACK CURRENTS.

Application filed November 4, 1925. Serial No. 66,703.

This invention relates to the control of railway trains by means of electro-magnetic waves or flux in a wayside conductor whether it be the track rails or an independent conductor extending along the track, the utilization of the track rails as conductor being shown by our co-pending application Serial Number 31,633, filed May 20, 1925, and the utilization of an independent conductor being shown in the Thomas E. Clark Patent No. 1,242,144, dated October 9, 1917.

10

In both of these systems, a transmitter of high-frequency high-potential current is positioned adjacent the end of each block into which the track is divided and the transmitting instrumentalities are constructed so as to embody adjustable devices which control the wave lengths of these currents so that the oscillating track circuits will be in tune with the collector coils mounted on the locomotive. We have found that the instrumentalities on the locomotives can easily be tuned to resonance with 20 standard transmitting devices located at a central station such as a round house, and that the "pitch" of such locomotive instrumentalities will therefore be uniform. But we have found that when the track instrumentalities are tuned previously to being 25 installed along the track, the wave lengths of the currents propagated in the rails will vary greatly by reason of the differences in impedance or conductivity of the rails and 30 also because of the differences in the character of the ballast, cross ties and the many other factors, both known and unknown.

It is therefore necessary to adjust or tune these track stations to a predetermined 35 standard so that the current propagated in the track conductors of each block or section will be the same as to wave length as that of all the other stations and that it will be of sufficient power to properly affect the 40 instrumentalities on the locomotives in use on that particular stretch of track.

In the accompanying drawing, we have 45 diagrammatically shown the two rails 1 and 2 of a track on which the traffic is supposed to move in one direction, that is, from right to left, these rails being divided into blocks by the insulations 3. The transmitting or transforming mechanism comprises a vacuum tube 38 having a plate 45, a grid 42 and a filament 37. This filament is heated 55 by a battery 13 whenever its circuit is closed, which occurs when the rail block to which the relay 7 is connected, is occupied, the relay being short circuited thereby which permits its armature α to close the circuit over 60 the wire 12, filament 37, adjustable resistance 39, wires 14 and 27, armature α and wire 11.

The main oscillating circuit consists of the battery 36, wire 14, resistance 39, filament 37, the gap between it and the plate 45, wire 48, coil 47, and wire 46 to the battery. The frequencies and wave lengths are controlled by the adjustable condenser 50 which shunts the plate coil 47. This battery 70 36 is usually termed the "B" battery and is preferably of 350 voltage. Any other proper source of current may be employed. The grid 42 connects to the circuit of the battery 13 by means of the grid leak 44 and 75 condenser 43 and the grid coil 40, and this circuit, together with the condenser 50, controls the production and rate of the oscillations.

The loading coil 52 connects to the wires 80 5 and 6, which connect the relay 7 to the rails, by means of wires 32 and 33, a condenser 35 being provided to prevent the passage of direct signal currents and the short circuiting of the track circuit. This coil 85 52 and its connecting wires, the rails 1 and 2 of the controlled section between the wires 5 and 6 and the condenser 20, and this condenser 20, constitute the output oscillating circuit. The electro-magnetic waves of this 90 circuit may be used to affect instrumentalities on the locomotive passing over this track section and which are tuned to the frequency of said waves, at which time, the leading pilot axle of the locomotive and 95 the wheels thereon affect these wave lengths to some extent.

In order to render the wave lengths of the electro-magnetic currents in the rails as 100 nearly uniform as possible, the loading coil is formed to have such an excess of millihenrys of inductance in proportion to the inductance of the rail section between the wires 5 and 6 and the condenser 20, that the total inductance of the active oscillating 105 circuit is not materially affected by the change in length of the rail portion thereof by a locomotive moving along the section

from the condenser 20 toward the insulations 3.

The lines of force seem to travel spirally around the rails 1 and 2 in opposite directions in zones of considerable diameter, these waves being indicated by the lines 23. At the same time, other lines of force seem to pass from one rail to the other in the form of an arch.

- 10 We have shown a car 55 on the rails 1 and 2 and the deck of this car carries a pair of collector coils 57 and 58 which are positioned so that their axes are substantially tangent to the spiral flux 23 of the electro-magnetic currents in the rails 1 and 2. A wave meter 59 on this car connects to one of these coils and to the adjustable condenser 60 and is tuned to resonance with the standard or test track installation used to standardize the locomotive installations.

The wave meter can be brought to the standard reading when the car is in the track section of the track installation to be tested by adjusting the condenser 50, and at the same time, the amp-meter 61 indicates the strength of the current in this oscillating circuit. If the current is lighter than necessary, the condenser 20 may be moved toward the insulations 3, but if heavier, the condenser is moved farther away, for the longest possible operative section is always desired for this work as it insures the operation of the instrumentalities on the locomotive.

- 35 It is, of course, not necessary to transport the wave meter on a vehicle, as it may be transported in any other desired manner, and so long as a standard of comparison is employed by means of which the oscillating circuits of the track installations may be tuned to produce electro-magnetic currents of the same wave lengths, any such standard may be employed. But it must be a measuring device which can be readily transported along the trackway and must embody means for so comparing each transmitting station with a standard station that all will propagate currents of the same wave lengths in the rails. These instrumentalities may 45 therefore be mounted on a locomotive and embody the collector coils which constitute part of the control mechanism thereof.

We claim:—

1. The process of rendering uniform the wave lengths of electro-magnetic currents 55 propagated in wayside conductors for the control of railway trains by track installations which embody resonant circuits and adjustable condensers whereby the circuits may be tuned, which consists in positioning adjacent the several wayside circuits of the trackway consecutively a wave meter which has been tested by a standard oscillating circuit, and adjusting said condensers until the several track installations all propagate currents of the same wave lengths.

2. The process of rendering uniform the wave lengths of electro-magnetic currents propagated in sections of railway tracks which are divided into blocks by insulating joints, the sections being defined by the insulation joints and by condensers connecting the rails, said currents being produced for the control of railway trains by track installations which embody transformer coils, resonant circuits and condensers whereby the circuits may be tuned, which process consists in positioning a wave meter adjacent the rails of such track sections and adjusting said condensers of the several track sections 70 until the indications of the wave meter at each section indicate the same current as that of a standard transmitting installation.

3. The process of rendering uniform the wave lengths of electro-magnetic currents 85 propagated in sections of railway tracks which are divided into blocks by insulating joints, the sections being defined by the insulation joints and by condensers connecting the rails, said currents being produced for 90 the control of railway trains by track installations which embody transformer coils, resonant circuits and condensers whereby the circuits may be tuned, which process consists in positioning a wave meter adjacent 95 the rails of such track sections and adjusting said condensers of the several track sections until the indications of the wave meter at each section indicate the same current as that of a standard transmitting installation 100 and in moving the condenser between the rails along the track until the current so propagated is of predetermined strength.
